UNITED STATES PATENT OFFICE

WALTER M. CROSS, OF KANSAS CITY, MISSOURI, ASSIGNOR TO CROSS COAL-O-MATIC COMPANY, OF KANSAS CITY, MISSOURI, A CORPORATION OF MISSOURI

UNDERFEED STOKER

Application filed June 23, 1930. Serial No. 463,212.

This invention relates to improvements in underfeed stokers, and refers more particularly to a stoker which has provision for supplying air under pressure both to the combustion pot of the stoker and an auxiliary supply from the same source to the tuyère grates surrounding the combustion pot, which auxiliary air supply is normally at a lower pressure.

6 The invention further provides for the accumulation of slag or incombustible material around the combustion pot upon the tuyère grates by the positioning of the tuyère grates below the level of the upper edge of 15 the combustion pot, preventing the flowing back of the molten or liquid slag into the throat of the combustion chamber.

This application is a continuation in part of a previous application, Serial 318,022, filed November 18, 1928.

Fig. 1 is a side elevational view of the stoker positioned in a furnace, with parts in section to disclose the operating mechanism.

Fig. 2 is a view taken along the line 2—2 25 in Fig. 1, looking in the direction of the arrow.

Fig. 3 is a modified type of combustion pot in which auxiliary air holes of predetermined size are used in place of the adjustable 30 damper.

Referring to the drawing; a boiler 1, in which are flue tubes 2, is mounted within a furnace setting, the masonry in which is designated as 3. The combustion space in 35 the furnace 4 is available through a fire door 5. The stoker consists of a fuel hopper 6 and motor 7, driving a fan positioned within the casing 8. The fuel from the hopper is fed by means of a screw 9 through the tube 10 40 into the combustion pot 11. Around the fuel tube is an air duct, designated as 12, to which air is supplied under pressure by means of a fan 8, the air being discharged into the combustion pot through a plurality of 45 tuyères 13 in the upper part of the combustion pot. Air supplied in this manner maintains the proper combustion conditions in combination with the fuel supplied from the hopper.

50 In the air duct 12, in a location beneath

the combustion pot, is a port 14, closed by a damper 15. This damper is pivoted at 16 and is manipulated manually by means of a rod 17, which is fastened to the damper at the opposite end from the pivot point 16. 55 By regulation of this damper by means of the rod 17, the auxiliary air which is released from the duct 12 into the space 17' beneath the tuyère grates 18, is positively regulated and controlled.

60 The function of the grates 18 which surround the combustion pot is to support the burning fuel and slag discharged from the combustion pot during the operation of the stoker. Lugs or supports 19 are positioned 65 both on the combustion pot and on the side of the furnace setting at different heights so that the grates may be lowered or raised according to the requirements of operation.

66 In the operation of an underfeed stoker 70 such as that shown, considerable difficulty has been experienced due to the draining of the slag back into the combustion pot. This slag accumulates in the bottom of the combustion pot or retort, and hardens, at times interfering with the operation due to freezing of the screw 9 in the fuel tube 10. By lowering the tuyère grates 18 and furnishing space for the accumulation of the burning fuel, ash and 75 slag, this tendency for the slag to drain back 80 into the combustion pot has been entirely eliminated.

85 In practice, to assure proper operation over a burning period of 24 hours, the tuyère grates 18 are sufficiently depressed to permit the accumulation of the slag for that period. The character of the coal used will determine the amount of slag accumulated within a given time, and there is provided, therefore, the adjustable arrangement of the grates. In 90 other words, when the ash content or slag content in the fuel is high, the grates will be depressed considerably lower than when the ash content is low. With such coal as is available to the vicinity of western Missouri and eastern Kansas, depression of the grates 6 or 8 inches below the upper lip of the combustion pot has been found as a satisfactory position for the tuyère grates 95 for operation over a period of 24 hours. An-

other factor to be considered, of course, is the size of the furnace setting or the square foot area available for the overflow material.

In the vertical portions of the grates as shown in my previous application are air ducts which permit the passage of the auxiliary air through the material collecting upon the grates. During the operation of the stoker, the main draft is supplied to the combustion pot to the fuel burning therein, through the tuyères 13, while the auxiliary air supply spilling through the port 14 furnishes air normally under lower pressure to the combustible material supported by the grates 18.

15 In place of a damper as shown at 15 in Fig. 1, there may be used a combustion pot such as shown in Fig. 3, having air ports 20 of a predetermined size. In place of two ports, a single port may be used, or a plurality of ports of any configuration which will supply a predetermined amount of air to the tuyère grates. This air constitutes an auxiliary air supply corresponding to the air supplied through the duct 14 as shown 25 in Fig. 1, the opening of which air port is controllable by the damper.

As the slag and ash accumulates on the tuyère grates 18, the resistance to air going 30 through the grates becomes relatively greater and the pressure in the retort or combustion pot and the air pressure supplied to the grates becomes more nearly equalized. This tendency toward equalization of the pressure assures the proper air supply to the tuyère 35 grates and, consequently, the burning and consumption of any combustible material upon the grates. By having the air supplied from a common source as shown, the air draft supplied to the combustion pot and the air draft supplied to the tuyère grates, is 40 controlled as to combustion requirements in the retort and on the grates by the accumulation of slag upon the tuyère grates. This 45 slag reducing the size of the air ports through which air must pass through the tuyère grates, reduces also the differential pressures maintained upon the retort and in the space under the tuyère grates, thus providing an 50 automatic control of the air supplied to the grates and to the retort.

Underfeed stokers of this type, when used either for commercial or domestic use are at 55 times rendered inoperable, particularly when burning coal having an ash of relatively low melting point and where the percentage of ash content in the coal is relatively high due to the draining back of the slag into the combustion pot. Since providing the space on 60 the tuyère grates for the ash accumulation and positioning the grates considerably below the rim of the retort, numerous service calls occasioned previously by clogging of the retort and screw with molten slag and 65 ash have been eliminated.

The removal of slag and clinker from the fire box while the stoker is in regular operation causes loss of fuel which is drawn out with the slag, and at such times there is discharged from the fire door objectionable gaseous odors which permeate the living space in the building. An outstanding advantage of the present arrangement is that no clinker or slag need be removed while the stoker is in operation, but instead the operator can 75 clean the ash and clinkers out any time in the early morning when the fire box of the furnace is cold and the coal or combustible material burned from the ash which has accumulated on the tuyère grates.

Furthermore, during periods of light firing, the depressing of the tuyère grates below the rim of the retort permits the accumulation of several days discharge from the retort without cleaning the material from the tuyère 85 grates.

I claim as my invention:

1. In an underfeed stoker, a combustion pot, an air supply means surrounding the combustion pot, a plurality of vertically spaced lugs on said air supply means, an air chamber having walls surrounding said air supply means, a plurality of vertically spaced lugs on said walls, the lugs on said air supply means and the lugs on said walls providing 95 means for adjustably positioning said grates vertically below the combustion pot rim.

2. In an underfeed stoker, a combustion pot, an air supply means surrounding the combustion pot, a plurality of vertically spaced lugs on said air supply means, an air chamber having walls surrounding said air supply means, a plurality of vertically spaced lugs on said walls, the lugs on said air supply means and the lugs on said walls 105 providing means for adjustably positioning said grates vertically below the combustion pot rim, and means for bleeding air from said air supply means into said air chamber.

3. In an underfeed stoker, the combination 110 including a fire box, a combustion pot positioned therein, grates surrounding said combustion pot, a plurality of vertically spaced supporting means positioned in said fire box to support said grates whereby said grates 115 may be adjustably positioned below the rim of the combustion pot to permit the accumulation of unconsumed material on said grates and thus preclude it from clogging said combustion pot.

In testimony whereof I affix my signature.
WALTER M. CROSS.
